UNITED STATES PATENT OFFICE.

GEORGE F. BLAKE, OF BELMONT, MASSACHUSETTS.

CHECK-VALVE.

SPECIFICATION forming part of Letters Patent No. 270,573, dated January 16, 1883.

Application filed September 26, 1882. (No model.)

To all whom it may concern:

Be it known that I, GEORGE F. BLAKE, of Belmont, county of Middlesex, State of Massachusetts, have invented an Improvement in 5 Check-Valves, of which the following description, in connection with the accompanying drawings, is a specification.

My invention relates to a check-valve which is especially intended for use in a branch from 10 the exhaust-pipe of a condensing-engine, the said valve opening toward the atmosphere when the condenser and air-pump of the engine fail to maintain the pressure in the exhaust-pipe below that of the atmosphere, or when it 15 is desired to run the engine non-condensing.

The object of my invention is to prevent the valve from hammering its seat; and it consists partly in the combination, with the valve and its seat, of a piston connected with the valve- 20 stem, and a cylinder therefor connected with the interior of the valve-casing. The upper end of the cylinder referred to opens directly into the valve-casing, and the lower end thereof is closed. The piston on the valve-stem fits 25 loosely in the cylinder, and is provided with a small passage controlled by a downwardly-opening valve, which permits the water of condensation collected in the lower part of the valve-case to pass down into the cylinder below 30 the piston when the valve is raised from its seat, and the said water in the cylinder retards the movement of the valve as it returns to its seat, preventing concussion, the water below the piston having its only exit between 35 the cylinder and piston.

Figure 1 is a vertical longitudinal section of a valve embodying this invention; Fig. 2, an under side view of the piston at the end of the valve-stem; and Fig. 3, a diagram illustrating, 40 in plan view, the relation of the valve to the exhaust-passages of the engine.

The casing A, having inlet and outlet openings 2 3, and a partition, a, between them provided with the valve port and seat b, may be of 45 any suitable or usual construction, it being shown in this instance as provided with a removable cover or bonnet, c; for the insertion of the valve d, the upper portion of the stem e of which travels in a guide, f, attached to the 50 said bonnet c.

The lower portion of the casing A is pro-

vided with a cylinder or dash-pot, g, shown as made in a separate piece, having a flange, h, for attaching it to the said casing, which has a suitable opening to receive it, the said cylinder being closed at its lower end and opening directly into the casing A at its upper end. The lower end of the valve-stem has connected therewith a piston or plunger, i, loosely fitted in the cylinder g, and provided with a small 60 passage, k, controlled by a valve, m, shown as consisting of a flexible strip of metal, opening downward, to permit a free passage of fluid through the opening k from the interior of the casing A into the cylinder g below the piston, 65 but preventing the flow thereof in the opposite direction. The cylinder g may be cast in one piece with the casing A.

In operation the valve is intended to be placed, as shown in Fig. 3, in the outboard 70 exhaust-pipe n, or pipe leading from the exhaust-pipe o, that connects the engine and condenser, into the atmosphere, so that the pressure of the atmosphere will act on the valve d to seat it, except when the exhaust-pressure 75 acting on the under side of the valve d is greater. The lower portion of the casing A will become filled with water of condensation, and when the pressure of the exhaust exceeds that of the atmosphere it will raise the valve 80 d. At the same time the pressure above the piston i will open the valve m and cause the said water to flow through the passage k and fill the cylinder g below the said piston i. If the pressure of the exhaust is suddenly diminished, 85 the valve d is closed by its own weight and the pressure of the atmosphere; but the downward movement is checked by water in the cylinder g beneath the piston i, which permits the said movement to take place only as 90 fast as the water can escape from the cylinder around the piston, the water thus retarding the downward movement and preventing concussion of the valve on its seat.

By properly proportioning the cylinder or 95 dash-pot and piston i and the passage through the latter all possibility of injury to the seat caused by its being hammered by the valve can be prevented.

By locating the valve-seat, as shown, between 100 the valve and piston, and having the valve seat downwardly upon its upper surface, the

movement of the valve in seating is positively resisted by the fluid entrapped beneath the piston, the said movement taking place only as fast as the liquid can escape around the piston.

I am aware that previous to this invention valves have been controlled in their seating movement by a connected piston operated in a cylinder connected with the valve-casing, 10 and do not broadly claim such construction.

I claim—

1. The valve-casing and valve-seat therein, and the valve seating on the upper surface of the said valve-seat, and the piston connected 15 with the said valve, combined with the cylinder or dash-pot, co-operating with the said piston and opening into the said valve-casing,

the valve-seat being located between the valve and piston, as described, substantially as and for the purpose set forth.

2. The valve-casing, seat therein, and cylinder or dash-pot connected therewith, combined with the valve and its attached piston provided with a passage, and a valve controlling the said passage, to operate substantially as 25 described.

In testimony whereof I have signed my name to this specification in the presence of two subscribing witnesses.

GEO. F. BLAKE.
